UNITED STATES PATENT OFFICE.

GEORGE BUTLER, OF CINCINNATI, OHIO.

CAR-COUPING.

SPECIFICATION forming part of Letters Patent No. 253,838, dated February 21, 1882.

Application filed August 12, 1881. (No model.)

To all whom it may concern:

Be it known that I, GEORGE BUTLER, of Cincinnati, Hamilton county, Ohio, have invented certain new and useful Improvements 5 in Car-Couplings, of which the following is a specification.

My invention is designed as an improvement upon the devices covered by Letters Patent No. 213,974, granted to me April 8, 1879, and its 10 purpose is to protect the key at the rear of the rear spindle from injury and render it more durable.

The precise nature of my present invention will be apparent from the drawings and the following description.

Referring to the drawings, Figure 1 is a perspective view of the under side of my invention; and Fig. 2 is a top view, partly in section. Fig. 3 is a detached view of one of the 20 features constituting the improvements over my Letters Patent No. 213,974.

A metallic case or cylinder, M, composed of two members, C C', is provided, and is here shown having a rectangular exterior and cylindrical internal conformation. This case is suitably secured to the car. In the present instance it is placed between the usual draft-timbers or sills, A A, the case being made of a desired size and broad enough, or the draft-timbers 25 brought near enough together, to admit of the case being fitted snugly between and against the timbers or sills. The case or cylinder is provided with projecting tongues c c, each of which fits snugly in a groove in its respective adjacent side timber, and the case is further secured in position between and to the timbers by means of the bolts D. The front and back walls of the cylinder or case have in their parting-line circular orifices E, counterbored for the 30 reception of correspondingly-formed sleeves or thimbles F F', the cylinder or spring-case being constructed, as shown, to correspond to the diameter and length of the spring H, together with washers I I'. The spring H is inserted 40 within the case between the washers I I', and presses said washers snugly against the inner walls of the cylinder. The washers I I' form a firm bearing for the spring H, and also, when at rest, operate to retain the sleeves F F' in 45 position within the counterbores, each washer 50

also operating as a flange or extension of its adjacent sleeve, the flanged necks of said sleeves preventing the passage without or beyond their proper position within the circular orifices before mentioned, as clearly shown in Fig. 2. After the case, with its necessary appendages, is 55 in position and secured to the car the rod G may be inserted in the draw-head K, said rod being securely retained therein by the head g, after which said rod may be passed through 60 the case, sleeves, and washers, and the inclosed-spring mechanism, as shown in Fig. 2, and secured therewith by a key, K'. The draw-head K is here shown as resting upon the usual carry-iron, B, connected to the draft-timbers A A. 65 The rear end of the draw-head is enlarged preferably to nearly the diameter of the spring H, the object of which is to form a good bearing-surface, so that there may be no danger of derangement or fracture of the spring-case m or 70 its appendages.

It is plain that the spring or its adjacent attachments are not disturbed by the withdrawal of the rod G for the purpose of substituting a new head for a broken one or for other cause. 75

The spring-case may be withdrawn for repair or inspection by first removing the draw-bar and screw-bolts and then withdrawing the case vertically from its place between the draft-timbers. After liberation, as above, the two halves 80 of the case may be separated, so as to fully expose the spring and other contents.

The device as described thus far is similar to the device covered by my aforementioned Letters Patent, the purpose of said device being to prevent the destruction of the spring by undue jamming, this advantage being obtained by the end of the draw-head on the one side coming into contact with the front wall, y, and the key K' coming in contact with the back 90 wall of the box C C', according as the draw-head receives a thrust or draft strain, before the different coils of the spring come in contact with each other, and thus the spring cannot be jammed. I have, however, found in practice that the key K' is liable to be bent or broken by continued striking against the spring-box, as a space equal to the thickness of the sleeve F is left between the point where the key bears 95 against the wall of the box and the point where it 100

receives support from the rod G, and a greater purchase is therefore brought to bear upon the key than if no such space were left. To overcome this objection, I have devised the means which constitute the principal feature of my present invention. This consists in providing the sleeve F at its outer end with a circular flange or collar, J; and this flange, instead of the key K', comes in contact with the end of the box C C', and thus very much of the strain is removed from the key K', as the surface against which it bears extends down to the point where the key receives its support from the rod G. Great benefit is therefore derived from the said improvement.

As a further means of strengthening my device and guarding against damage from a sud-

den and severe end-thrust, I construct the draft-timbers A A with shoulders h, against which the rear end of the spring-box rests, as shown, 20 and this, in connection with the tongues c and their corresponding grooves, gives great strength to the device.

What I claim as new and of my invention, and desire to secure by Letters Patent, is—

In a car-coupling device, the combination of the case M and the sleeve F, provided with flange or collar J, and the draft-rod G and key K', and an appropriate draw-head, substantially as and for the purposes specified.

GEO. BUTLER.
